APPARATUS FOR SEALING CARTONS

Francis N. Todd and Kenneth W. Emerson,
Honolulu, Territory of Hawaii, assignors to
Hawaiian Pineapple Company, Limited, Hon-
olulu, Territory of Hawaii, a corporation of the
Territory of Hawaii

Application August 1, 1939, Serial No. 287,783

20 Claims. (Cl. 93—6)

The present invention relates to the closing and sealing of cartons, and more particularly to apparatus for inserting and securing filler strips in the carton.

5 The conventional fibreboard carton employed for packing canned goods and the like is rectangular in shape having side and end hinged flaps forming the top and bottom. The combined width of the side flaps is substantially 10 equal to the width of the carton but to avoid waste of carton material, the end flaps are generally made shorter than the length of the carton and leave a considerable gap between their ends when closed. The result is an uneven surface at 15 top and bottom of the carton, usually the inner surface, as the side flaps are generally sealed over the end flaps for reasons of appearance and because the spaced end flaps would be apt to catch and tear open during shipment if on the outside of the carton.

This uneven inner surface at top and bottom of the packed cartons is a cause of considerable damage to the contents during shipment, particularly in the case of such articles as canned 25 goods, bottles and the like. In the case of canned goods, for example, the cans in the vertical central layers are, due to the gap at the bottom of the carton, offset below adjacent layers and are capable of greater vertical shifting because of 30 the increased depth of the carton at the central gaps. As a result, the cans in these layers are liable to interlock their end rims or chines, and dent each other and scuff their labels when the 35 carton is subjected to rough handling. For similar reasons, like damage and even breakage is apt to result with bottles and other fragile containers.

To remedy this difficulty, it has heretofore been proposed to provide the carton blank, prior to 40 folding, with tabs secured to a surface at the portions intended to constitute the inner surface of the side flaps, in position to lie within the gaps between the end flaps when the carton is 45 folded. While cartons formed from such blanks are generally satisfactory as regards a smooth inner surface at top and bottom for level riding of the contents, the expense of securing the tabs properly to the blanks is great, requiring special 50 treatment and a time-consuming hand operation or complicated expensive machinery so that the cost of the blank is increased substantially more than the cost of the tab material added. A further substantial disadvantage of this method is 55 that the thickness of the blanks is doubled so

that the space required for shipment and storage is likewise doubled.

Cartons are generally packed with both the top and bottom flaps in unsealed condition and are then transferred to a machine which simultaneously seals both the top and bottom of the carton. In the usual carton sealing machine, the packed carton is advanced along a slide on its bottom end flaps, and means disposed at the sides 5 of the slide successively open the side flaps, apply 10 adhesive to their under surface and fold them back over the end flaps in position to be permanently sealed thereto by subsequent pressure applying mechanism.

In an application of Harry S. Fox and Kenneth 15 W. Emerson, Serial Number 287,776, filed simultaneously herewith, there is disclosed means for inserting a filler strip in the gap between the end flaps at the top of the packed carton as it is advancing from the flap opening to the flap closing 20 means of a sealing machine of the type just referred to. It is an object of the present invention to provide means for inserting a filler strip in the gap between the end flaps at the bottom of a packed carton while it is advancing 25 through such a sealing machine, so that, by use of the means of the present application in conjunction with that of the said application Serial Number 287,776, the gaps may be filled and the 30 flaps sealed at both the top and the bottom of the carton on a single passage of the carton through the machine and without increasing the time required for the sealing operation.

Other objects and advantages of the invention will be apparent from the ensuing more particular description taken in conjunction with the appended drawings wherein:

Fig. 1 is a plan view of a part of a carton sealing machine embodying filler strip feeding and inserting means of the invention, with the parts 40 for sealing the top flaps broken away;

Fig. 2 is a side elevation of the part of the machine between the lines A—A of Fig. 1;

Fig. 3 is an enlarged plan view of part of the machine between the lines A—A of Fig. 1, with 45 parts broken away to show the tab feeding and inserting mechanism;

Fig. 4 is an elevational view on the line 4—4 of Fig. 1 looking in the direction of the arrows;

Fig. 5 is a detail view, partly in elevation, 50 partly in section, of certain of the parts shown in Fig. 3.

Referring first to Fig. 1, it will be seen that the machine has an elongated main frame structure 100 which supports a central slide 101 along 55

which the packed cartons are continuously conveyed from left to right in Fig. 1 between guide rails 102 by means of regularly spaced pusher bars 103 secured at their ends to endless sprocket 5 chains 104 extending along opposite sides of the slide over driven and idler sprocket wheels (not shown) at opposite ends of the slide. The cartons are fed onto the forward end of the slide 101 between successive pusher bars 103 resting on 10 their bottom inner flaps with the bottom outer flaps extending downwardly at the sides of the slide, suitable means for this purpose (not shown herein) being shown and described in United States Patent No. 2,095,258 dated October 12, 15 1937.

The cartons are advanced along the slide into the path of a pair of front plows 105 secured to a cross shaft 106 at opposite sides of the slide, these plows entering between the downwardly extending bottom side flaps and raising them to substantially horizontal position between rearward horizontal flange extensions of the plows and top plates 107. As the cartons are advanced beyond the front plows 105 the bottom side flaps are carried in horizontal position over gluing rollers 108 secured to a cross shaft 109 and fed by glue tanks 110, said rollers 108 applying a coating of glue to the under or inner surface of said flaps. As the carton approaches the rear end of the slide 101, the bottom side flaps encounter a pair of rear plows 111 which turn them back under the slide to partially closed position. On further advancement, the cartons pass off the rear end of the slide 101 onto a second slide or conveyer (not shown) on which they rest on their bottom side flaps which, under the weight of the carton, or further pressure applied thereto, acts to seal the bottom side flaps to the bottom end flaps.

40 The case sealing apparatus so far described is substantially similar to that shown and described in the aforementioned Patent No. 2,095,258 to which reference may be had to supplement the foregoing description. Reference may also be had to said patent for illustration and description of means for sealing the top flaps of the carton as its bottom flaps are being sealed by the means above described, and to the aforesaid application Serial Number 287,776 for illustration and description of means for inserting a filler strip in the gap between the upper end flaps of the carton as it is advanced through the machine.

According to the present invention there is attached to the apparatus so far described means for inserting a filler strip in the gap between the bottom end flaps of a carton as it is advanced along the slide 101 toward the flap closing means, preferably, as shown, subsequent to the flap opening plows. Referring to Figs. 1 and 3, it will be seen that there is interposed in the slide 101 a transverse slot or aperture 10 somewhat longer and wider than a filler strip to be inserted, and preferably, as shown, extending entirely across the slide. Centrally of the slide 101 to the rear of the transverse slot 10 is a longitudinal slot 11 communicating with the slot 10.

To the frame 100, below the slot 11 there is bolted a standard 12 (see Fig. 4) having upwardly projecting side arms 13 to which are fixed the opposite ends of a pivot pin 14. Pivotally mounted on the pin 14 by means of a sleeve 15 to lie within the communicating slots 10 and 11 is a generally T-shaped plate 16, having a raised substantially flat forward end forming a platform 17 disposed in the slot 10 and a raised rearward end

forming a cam 18 adjacent the rear end of the slot 11 (see Fig. 5). The weight of the portion of the plate forwardly of the pivot center is somewhat greater than that at the rear of the pivot line, so that normally the plate assumes a tilted position shown in dotted lines in Fig. 5, against a suitable stop (not shown), with the platform 17 at least a filler strip's depth below the surface of the slide 101, and the cam 18 above it. The top surface of the platform 17 and the cam 18 are disposed substantially in a single plane so that when the plate is pivoted to horizontal position shown in full lines in Fig. 5 these surfaces are substantially flush with the surface of the slide 101. The distance between the rear edge of the platform 17 and the front edge of the cam 18 is approximately equal to that between the front end of a carton and the adjacent edge of the gap between its bottom end flaps.

From the foregoing it will be evident that as the carton A is advanced along the slide 101 over the slot 10 and slot 11, its front end strikes the cam 18, depressing the cam 18 and raising the platform 17 to the horizontal position shown in full lines in Fig. 5, with their top surfaces substantially flush with the top surface of the slide 101. It will further be evident that, due to the identity of the distance of the platform 17 from the cam 18 and the distance of the gap G from the front of the carton, the platform 17 will rise to its upper position at the moment the gap G is registered over the slot 10 in the slide 101. If, therefore, as shown in Fig. 5, a filler strip F is positioned on the platform 17 in registry with the slot 10 in advance of the engagement of an advancing carton with the cam 18, it will be projected upwardly through the slot 10 into the gap G of the carton with its bottom surface substantially flush with the bottom surface of the end flaps E on engagement of the front end of the carton with the cam 18. In this position the filler strip F is engaged by the edge of the rear end flap E and pushed off the platform 17 onto the slide 101 along which it rides with the carton to the flap sealing mechanism, being held in the gap by the weight of the contents of the carton resting on it and the said rear bottom end flap E.

On the frame 100 at one side of the platform 17 there is mounted a horizontal slide 19 having an end adjacent the platform 17. Extending longitudinally through the slide 19 is a slot 20 in approximate alignment with the longitudinal center line of the platform 17. Mounted on the slide 19 is a magazine 21 adapted to hold a stock of filler strips F centered over the slot 20 in end-wise relation to the platform 17. As best shown in Fig. 2, magazine 21 comprises an end plate 22 fixed to the slide 19 intermediate its ends transversely over the slot 20, and side plates 23 secured to said end plate 22 and slide 19 in parallel relation with the slot 20 and at equal distances at each side thereof. To accommodate stacks of filler strips of different widths, the plates 23 are adjustable toward and away from the slot 20. To this end, the slide 19 is provided with a series of grooves 24 at equal intervals from the slot 20 adapted to receive the bottom edge of one of the plates 23 therein, and the end plate 22 is provided at the top and bottom with transverse rows of apertures 25, corresponding apertures in each row being vertically aligned and adapted to receive therein pins 26 projecting from the end of the plates 23 when the plates are positioned in one of the grooves 24. Plungers 27 vertically slidable in collars 28 fixed to the outer surface of 75

each plate 23 are pressed against the slide 19 by coil springs 29 extending between the plunger heads and the bottom of the collars 28 to releasably lock the plates against accidentally sliding 5 away from the plate 22 and displacing the pins 26 from the apertures 25.

When it is desired to shift the position of the plates 23, the plungers 27 are raised by their handle portions 27' and the plates are then slid 10 outwardly along the grooves 24 until the pins are released from the apertures 25, the plates then being free for reengagement with another set of grooves 24 and apertures 25. Handles 23' are fixed to the outer surface of the plates 23 to 15 facilitate adjustment.

Extending through the slot 20 is an endless sprocket chain 30, extending over an idler sprocket wheel 31 mounted on a horizontal axis below and between the adjacent ends of the slide 20 19 and the platform 17, and a driven sprocket wheel 32 mounted on a horizontal axis below the opposite end of the slide 19 (see Figs. 3 and 4). As shown in Fig. 3, sprocket wheel 31 is rotatable on a stub shaft 33 fixed to a bracket arm 34 bolted to an adjustable bracket 34a which bracket forms a part of the support for guide rail 102. On the shaft 33 between the hub of the sprocket wheel 31 and the bracket arm 34 there is pivotally mounted a collar 35 to which is fixed a bracket 25 arm 36 having at the opposite end a collar 37 in which is rotatably mounted driven shaft 38 on one end of which is fixedly mounted the sprocket wheel 32.

To the opposite end of the driven shaft 38 there 35 is secured, by means of a universal joint 39, one end of an adjustable link 40, the other end of which is connected, by a second universal joint 41, with an end of a stub shaft 42 rotatably mounted in a standard 43 fixed on a flange 44 bolted to the frame 100 forwardly of the sprocket 40 wheel 32. A bevel gear 45 fixed to the stub shaft 42 is driven by meshing bevel gear 46 fixed to a stub shaft 48, the shaft being continuously driven by means of driving connections (not shown) to a convenient driven element of the sealing machine. Shaft 38 and sprocket wheel 32 are therefore continuously driven from gear 46 by means of gear 45, shaft 42, and link 40. The universal joint and link connection between the shafts 38 45 and 42 permits the shaft 38 to be periodically raised and lowered by pivoting the bracket arm 36 about the shaft 33 for a purpose and by means 50 now to be described.

Secured to the sprocket chain 30 is a pusher pin 50 (see Fig. 4) projecting outwardly therefrom. When the sprocket wheel 32 is in its normal lowered position, chain 30 is sufficiently below the top of slot 20 so that the upper end of pin 50 is also below the top of slot 20 and passes freely under the bottom filler strip in the magazine 21. However, when the sprocket wheel 32 is raised, as shown in Fig. 4, pin 50 is raised above the top of slot 20 and engages the outer end of the bottom filler strip F of the stack in the magazine, pushing it through a suitable opening 22' in the base of end plate 22 of magazine 21 (see Fig. 2) along slide 19 over slot 20 and onto platform 17 where pin 50 drops below the end of the filler strip, passing downwardly over sprocket wheel 31 through a slot 20' in the end 70 of platform 17. The filler strip is then raised into the gap G of an advancing carton by engagement of the front end of the carton with the cam 18, as previously described.

75 In order that a filler strip may be thus fed onto

the platform 17 in each interval between passage of the rear end of one carton over the cam 18 and the arrival of the front end of the next succeeding carton over the slot 10, while the platform 17 is in lowered position, means are provided to govern the raising and lowering of the sprocket wheel 32 according to the position of these cartons on the slide.

Referring to Figs. 3, 4 and 5, it will be seen that bracket arm 36 which, as previously described, is pivoted on shaft 33 to raise and lower the sprocket wheel 32, rests upon an end of a cam arm 51 which in turn rests upon a flange 52 bolted to frame 100 on which it is slidably between vertically projecting guide pins 53. On the end 15 of said arm 51 is a raised portion or cam 54 having a rounded inner edge over which the bracket arm 36 rides to upper position as the arm 51 is drawn forwardly of the machine and to lower position as said arm is returned rearwardly of the 20 machine. Adjacent its opposite end, said arm 51 rests slidably between vertical guide pins 55 on a flange 56 projecting from the frame 100, and at said end has a coupling 57 provided with a pin 58 slidable in a slot 59 in the end of an arm 60 25 fixed to a vertical stub shaft 61 rotatably mounted on the frame 100 adjacent one of the sprocket chains 104. A second arm 62 is fixed to the opposite side of the shaft 61 and projects over the slide 101 into the path of the cartons. A coil 30 spring 63 secured at one end to the shaft 61 and at the other end to adjacent frame structure tends to turn the shaft and arms 60 and 62 to the dotted line positions of Fig. 3.

As a carton travels along the slide 101 in the 35 direction of the arrow in Figs. 3 and 5, its front end encounters arm 62 in the dotted line position of Fig. 3 and pushes it out to the full line position of Fig. 3 where its outer end rides along the side of the advancing carton. As arm 62 is 40 turned to its full line position, arm 60 is also turned from its dotted line to its full line position drawing the cam arm 51 to the left as viewed in Figs. 3 and 5, raising bracket arm 36, by means of cam 54, which in turn raises shaft 45 38 and sprocket wheel 32, by means of collar 37, for engagement of continuously traveling pusher pin 50 with the bottom filler strip of the stack in magazine 21. Pusher pin 50 thereupon ejects the bottom filler strip onto platform 17 in position for insertion in the bottom gap of the advancing carton in the manner previously described.

To avoid ejection of more than one filler strip at a single actuation of the cam arm 51, the 55 drive to sprocket wheel 32 is so timed that sprocket chain 30 makes approximately one complete revolution about the sprockets 31 and 32 during the interval when the bracket arm 36 is in raised position which, in turn, is approximately the interval in which the advancing carton A is moved through its length along the slide 101, thus carrying its rear end past the end of the arm 62 permitting the arm 62 to swing back to dotted line position under the influence of 60 spring 63 and retracting cam arm 51 to lower bracket arm 36 and sprocket wheel 32. The drive of sprocket 32 is also so timed that chain 30 makes a certain number of complete revolutions while conveyer chains 104 are advanced the distance between successive pusher bars 103 along slide 101, so that pusher pin 50 is always just approaching the rear end of the bottom filler strip of the stack when sprocket wheel 32 is raised. As indicated in Fig. 3, the arm 62 is spaced 75

from the slot 10 along the slide 101 that it is brought to full-line position by the advancing carton A at approximately the time the rear end of the receding carton A' passes over the cam 18 5 to release the platform 17 to its lowered position in which it receives a filler strip from the pin 50 and holds it below the bottom of the advancing carton until the cam 18 is again actuated.

As shown in Fig. 4, a bracket arm 64 is attached 10 to frame 100 just in advance of the slide 19 and supports an idler roller 65 in position to engage the side flap S of an advancing carton and raise it sufficiently to clear the filler strip feeding mechanism.

15 It will be understood that the invention is not limited to the specific form of sealing machine shown but may be employed in conjunction with any slide along which the cartons are conveyed resting on their bottom end flaps with 20 their bottom side flaps held open. It will also be understood that the invention is not limited to the form and arrangement of parts shown and that changes may be made therein without departing from the spirit and scope of the invention.

25 We claim:

1. In apparatus for sealing cartons by securing outer flaps over unmeeting inner flaps, a slide, means for advancing a carton along said slide with an unmeeting pair of said flaps resting on 30 said slide, a slot in the slide adapted to register with the gap between the ends of said unmeeting inner flaps on passage of the carton thereby, and means operative on registry of said gap with 35 said slot to insert a filler strip into said gap through said slot.

2. In apparatus for sealing cartons by securing together overlapping pairs of side and end flaps, a slide, means for advancing a carton along said slide resting on an unmeeting pair of said flaps, a slot in the slide adapted to register with the 40 gap between the ends of said unmeeting flaps on passage of the carton thereover, means to raise a filler strip through said slot into said gap on arrival of the carton thereover, and means to 45 secure said overlapping pair of flaps to said filler strip lying in said gap.

3. In apparatus for sealing cartons by securing outer flaps over unmeeting inner flaps, a slide, means for advancing a carton along said slide resting on said unmeeting inner flaps with said 50 outer flaps open, a slot in the slide adapted to register with the gap between the ends of said unmeeting inner flaps on passage of the carton thereover, and means to raise a filler strip through said slot when said gap is registered 55 thereafter.

4. In apparatus for sealing cartons by securing outer flaps over unmeeting inner flaps, a slide, means for advancing a carton along said slide resting on said unmeeting inner flaps with said 60 outer flaps open, a slot in the slide adapted to register with the gap between the ends of said unmeeting inner flaps on passage of the carton thereover, means to raise a filler strip through 65 said slot into said gap on passage of the carton thereover, means to apply adhesive to the inner surface of said outer flaps, means to fold said outer flaps toward closed position as the carton approaches the end of the slide, and means to 70 seal said outer flaps to said inner flaps over said filler strip as said carton is advanced off said slide.

5. Apparatus for inserting a filler strip in the gap between the ends of a pair of unmeeting flaps of a carton, comprising a slide, means for

advancing the carton along the slide resting on said unmeeting flaps, a slot in the slide adapted to register with the gap between said flaps on passage of the carton thereover, and means operated in timed relation with said carton advancing means to raise a filler strip through said slot to horizontal position above said slide on registry of said gap over said slot. 5

6. Apparatus for inserting a filler strip in the gap between the ends of a pair of unmeeting flaps of a carton, comprising a slide, means for advancing the carton along the slide resting on said unmeeting flaps, a slot in the slide adapted to register with the gap between said flaps on passage of the carton thereover, means to position a filler strip below said slot, and means operated by the advancing carton to raise said filler strip through said slot to horizontal position above said slide on registry of said gap over said slot. 15

7. Apparatus for inserting a filler strip in the gap between the ends of a pair of unmeeting flaps of a carton, comprising a slide, means for advancing the carton along the slide resting on said unmeeting flaps, a slot in the slide adapted to 25 register with the gap between said flaps on passage of the carton thereover, a platform under said slot adapted to be raised therein to dispose its upper surface substantially flush with the upper surface of the slide, means to position a 30 filler strip horizontally on said platform while in lowered position, and means to raise said platform to upper position when the carton is advanced to register said gap over said slot whereby to lift said filler strip into said gap. 35

8. Apparatus for inserting a filler strip in the gap between the ends of a pair of unmeeting flaps of a carton, comprising a slide, means for advancing the carton along the slide resting on said unmeeting flaps, a slot in the slide adapted to 40 register with the gap between said flaps on passage of the carton thereover, a platform under said slot adapted to be raised therein to dispose its upper surface substantially flush with the upper surface of the slide, means to position a 45 filler strip horizontally on said platform while in lowered position, and means operated by the advancing carton to raise said platform to upper position when the carton is advanced to register said gap over said slot whereby to lift said filler 50 strip into said gap.

9. Apparatus for inserting a filler strip in the gap between the ends of a pair of unmeeting flaps of a carton, comprising a slide, means for advancing the carton along the slide resting on 55 said unmeeting flaps, a slot in the slide adapted to register with the gap between said flaps on passage of the carton thereover, a platform under said slot adapted to be raised therein to dispose its upper surface substantially flush with the 60 upper surface of the slide, a cam connected to said platform engageable with the front of a carton advancing on said slide over said slot to raise said platform into said slot, and means to feed a filler strip onto said platform before engagement of the next succeeding carton with said cam. 65

10. Apparatus for inserting a filler strip in the gap between the ends of a pair of unmeeting flaps of a carton, comprising a slide, means for advancing the carton along the slide resting on said unmeeting flaps, a platform pivotally mounted in said slide normally disposed with its forward end below the surface of the slide and its rearward end projecting above said surface in the 70 75

path of an approaching carton, said plate tiltable on engagement of a carton with said projecting rearward end to raise said forward end substantially flush with the surface of the slide, and 5 means to feed a filler strip onto the forward end of said plate while the rearward end of the plate is out of contact with a carton.

11. Apparatus for inserting a filler strip in the gap between the ends of a pair of unmeeting flaps of a carton, comprising a slide, means for advancing the carton along the slide resting on said unmeeting flaps, a slot in the slide adapted to register with the gap between said flaps on passage of the carton thereover, a tiltable platform having a forward end normally disposed below said slot and a rearward end normally projecting above the upper surface of said slide rearwardly of the slot in the path of the advancing carton, said rearward end of said platform 10 pressable by the advancing carton to raise said forward end into said slot with its upper surface substantially flush with the upper surface of the slide, and means to position a filler strip on the forward end of said platform for lifting through 15 said slot by engagement of a carton with the rearward end of the platform.

12. Apparatus for inserting a filler strip in the gap between the ends of a pair of unmeeting flaps of a carton, comprising a slide, means for advancing the carton along the slide resting on said unmeeting flaps, a slot in the slide adapted to register with the gap between said flaps on passage of the carton thereover, a magazine for a supply of filler strips at one side of said slide, and 20 means operated in timed relation with said carton advancing means to transfer a filler strip from said magazine under said slide as the carton approaches the slot and to raise said filler strip through said slot on registry of said gap thereover.

13. Apparatus for inserting a filler strip in the gap between the ends of a pair of unmeeting flaps of a carton, comprising a slide, means for advancing the carton along the slide resting on said unmeeting flaps, a slot in the slide adapted to register with the gap between said flaps on passage of the carton thereover, means controlled by a carton approaching said slot to transfer a 25 filler strip to a horizontal position under said slot in registry therewith, and means operated by the advancing carton to raise said filler strip through said slot on registry of said gap thereover.

14. Apparatus for inserting a filler strip in the gap between the ends of a pair of unmeeting flaps of a carton, comprising a slide, means for advancing the carton along the slide resting on said unmeeting flaps, a slot in the slide adapted to register with the gap between said flaps on passage of the carton thereover, a platform under said slot adapted to be raised therein to dispose its upper surface substantially flush with the upper surface of the slide, a magazine for a supply of filler strips at one side of said slide, and 30 means to transfer a filler strip from said magazine onto said platform in registry with said slot when said platform is in lowered position, and means to raise said platform to upper position when the carton is advanced to register said gap over said slot.

15. Apparatus for inserting a filler strip in the gap between the ends of a pair of unmeeting flaps of a carton, comprising a slide, means for advancing the carton along the slide resting on said unmeeting flaps, a slot in the slide adapted to reg-

ister with the gap between said flaps on passage of the carton thereover, a platform under said slot adapted to be raised therein to dispose its upper surface substantially flush with the upper surface of the slide, a magazine for a supply of filler strips at one side of said slide, means to transfer a filler strip from said magazine onto said platform in registry with said slot when said platform is in lowered position, and means operated by the advancing carton to raise said platform to upper position when the gap is registered over said slot. 5

16. Apparatus for inserting a filler strip in the gap between the ends of a pair of unmeeting flaps of a carton, comprising a slide, means for advancing the carton along the slide resting on said unmeeting flaps, a slot in the slide adapted to register with the gap between said flaps on passage of the carton thereover, a platform under said slot adapted to be raised therein to dispose its upper surface substantially flush with the upper surface of the slide, a magazine for a supply of filler strips at one side of said slide, a chute connecting a lower end of said magazine with the upper surface of said platform in lowered position, a passage for a filler strip through said end of the magazine, and means operative while said platform is in lowered position to eject a filler strip through said passage along said chute onto said platform. 10 15 20 25

17. Apparatus for inserting a filler strip in the gap between the ends of a pair of unmeeting flaps of a carton, comprising a slide, means for advancing the carton along the slide resting on said unmeeting flaps, a slot in the slide adapted to register with the gap between said flaps on passage of the carton thereover, a platform under said slot adapted to be raised therein to dispose its upper surface substantially flush with the upper surface of the slide, a magazine for a supply of filler strips at one side of said slide having an end adjacent said platform, a passage for a filler strip through said end of the magazine, and pusher means engageable with a filler strip in said magazine to force it through said passage onto said platform in lowered position. 30 35 40 45

18. Apparatus for inserting a filler strip in the gap between the ends of a pair of unmeeting flaps of a carton, comprising a slide, means for advancing the carton along the slide resting on said unmeeting flaps, a slot in the slide adapted to register with the gap between said flaps on passage of the carton thereover, a platform under said slot adapted to be raised therein to dispose its upper surface substantially flush with the upper surface of the slide, a magazine for a supply of filler strips at one side of said slide having an end adjacent said platform, a passage for a filler strip through said end of the magazine, an endless conveyer having a portion operating from the other end of the magazine to adjacent said platform, a pusher pin on said conveyer accessible to but normally clearing the bottom filler strip of the stack in the magazine, and means to lift said pusher pin to engage said bottom filler strip whereby to push said strip onto said platform. 50 55 60 65

19. Apparatus for inserting a filler strip in the gap between the ends of a pair of unmeeting flaps of a carton, comprising a slide, means for advancing the carton along the slide resting on said unmeeting flaps, a slot in the slide adapted to register with the gap between said flaps on passage of the carton thereover, a platform under said slot adapted to be raised therein to dispose 70 75

its upper surface substantially flush with the upper surface of the slide, a magazine for a supply of filler strips at one side of said slide having an end adjacent said platform, a passage for a 5 filler strip through said end of the magazine, an endless conveyer having a portion operating from the other end of the magazine to adjacent said platform, a pusher pin on said conveyer accessible to but normally clearing the bottom filler 10 strip of the stack in the magazine, and means to shift the position of said conveyer to engage said pin with said bottom filler strip whereby to push said strip onto said platform.

20. Apparatus for inserting a filler strip in the 15 gap between the ends of a pair of unmeeting flaps of a carton, comprising a slide, means for advancing the carton along the slide resting on said unmeeting flaps, a slot in the slide adapted to register with the gap between said flaps on

passage of the carton thereover, a platform under said slot adapted to be raised therein to dispose its upper surface substantially flush with the upper surface of the slide, a magazine for a supply of filler strips at one side of said slide 5 having an end adjacent said platform, a passage for a filler strip through said end of the magazine, an endless conveyer having a portion operating from the other end of the magazine to adjacent said platform, a pusher pin on said conveyer accessible to but normally clearing the bottom filler strip of the stack in the magazine, and means operated by an advancing carton to lift said pusher pin to engage said bottom filler strip whereby to push said strip onto said platform. 10 15
